UNITED STATES PATENT OFFICE.

HUGO JUNKERS, OF AIX-LA-CHAPELLE, GERMANY.

TWO-CYCLE INTERNAL-COMBUSTION ENGINE EMPLOYING LIQUID FUEL.

1,117,497.

Specification of Letters Patent. Patented Nov. 17, 1914.

Application filed August 28, 1908. Serial No. 450,775.

To all whom it may concern:

Be it known that I, HUGO JUNKERS, a subject of the King of Prussia, residing at No. 64 Brabantstrasse, Aix-la-Chapelle, in the Kingdom of Prussia, Empire of Germany, have invented certain new and useful Improvements in Two-Cycle Internal-Combustion Engines Employing Liquid Fuel; and I do hereby declare the following to be a full, clear, and exact description of the invention, such as will enable others skilled in the art to which it appertains to make and use the same.

The present invention has for its object to provide an engine for the development of power from liquid fuel such as hydro-carbon oils, and particularly from crude or so-called heavy oils, in such manner as to attain good thermic efficiency combined with the assurance of uninterrupted operation, good starting qualities and the possibility of controlling the speed and output of the engine over rather wide limits. To this end, a type of engine is employed in which the gas used for supporting combustion, and which I will hereinafter refer to as the air, is, without the admixture of any combustible material, compressed in the engine cylinder to a temperature well above the ignition point of the fuel employed, and the liquid fuel is then introduced in a finely divided form beginning at or near the end of the compression stroke, and continuing through the "dead point" and a portion of the working stroke, the duration of the admission of fuel in the working stroke determining the output of the engine. That is to say, the engine is of the slow combustion, or so-called "equal pressure" type, of which the well-known Diesel engine is the most prominent example. In the following portions of this specification I will use the term "slow combustion engine" in this sense, and in contradistinction to engines of the explosion type, that is, engines in which a combustible mixture is compressed and ignited either by the heat due to compression or by a suitable igniting device. I have found that the successful development of an engine of this slow combustion type and having capacities above indicated is depend-

ent primarily upon efficient compression approaching as nearly as possible ideal adiabatic conditions, which involves a rapid compression into a combustion space or chamber in which heat losses by conduction through the walls of the chamber are reduced to a minimum; and secondarily, upon efficient scavenging whereby the products of combustion are completely removed at each scavenging operation and soot-free combustion is attained, while at the same time the air is introduced in a cool and heavy state so that a maximum quantity of air is inclosed in the cylinder at the time compression begins. I have therefore employed, in the embodiment of my invention, a type of engine which is an adaptation of an already known type in such manner that it is enabled to fulfil the conditions just indicated. This engine is characterized by the employment of a cylinder of smooth bore without projections or recesses and in which the ratio of length to the volume is relatively great, and in which operate two opposingly working pistons, the pistons and cylinder being so proportioned to the intended speed of the stroke as to compress the air to a temperature well above the ignition point of the fuel employed before the fuel is introduced. The cylinder is provided with exhaust passages at one end and inlet passages at the other end, the passages being preferably controlled by the pistons and so shaped and arranged that the exhaust passages will open before the air passages are opened and will close after the air passages are closed. With this construction there is provided an effective cylinder space from which the products of combustion are driven out by a straight continuous air stream entering the working cylinder at one end and leaving it at the opposite end; and combustion takes place in a combustion chamber where the heat losses are reduced to a minimum since it has not only a relatively small wall area, but the hot piston faces constitute the greater part of that area, which is free from inlet and exhaust valves which would necessarily be cooled by the scavenging air. Furthermore the heating of the air charge is reduced to a minimum since the air does not pass over hot valve sur-

faces and at the beginning of the compression the effective cylinder chamber has a maximum cooled surface, *i. e.*, the walls of the cylinder which are cooled by the water jacket, so that the charge of air is cool and heavy and consequently of large amount.

In the accompanying drawings, which illustrate the preferred embodiment of my invention—Figure 1 is a longitudinal sectional view of the engine; Fig. 2 is a plan view; Fig. 3 is a sectional view on lines 3, 3 of Fig. 1; Fig. 4 is a sectional view on line 4, 4 of Fig. 1; and Fig. 5 is a typical working diagram of my improved engine in comparison with a diagram of a slow combustion engine in which but a single piston is employed.

To the frame 1 the working cylinder 2, the reach 3, the cylinder of the scavenging and charging air pump 4 and also the cylinder of the atomizing or vaporizing air pump 5 are secured, and supported by the props 6. The working cylinder 2 is provided with a cooling jacket 7 and the air pump 5 with a cooling jacket 8 and from which the cooling fluid may be conducted in any suitable manner. In the frame 1, a double-throw crank shaft 9 is journaled to the middle crank of which the working piston 10 is connected by means of the connecting rod 11 and the piston rod 12, these rods being joined by the cross-head 13 which slides in the cross-head guides 14. The other working piston 15 is connected by the piston rod 16 to the reciprocating yoke 17 mounted in guides in the reach 3 and connected by the rods 18 to the cross-heads 19 which slide upon the slides 20 and are connected through the connecting rods 21 to the two outer cranks displaced about 180° from the middle crank of the crank shaft 9. The connecting rod 11 and the piston rod 12 on the one hand and the connecting rods 22, side rods 18 and piston rods 16 on the other hand are so dimensioned with respect to the dimensions of the cylinder and pistons that when the pistons 10 and 15 have reached their position of closest approach the air will have been compressed to a temperature sufficiently high to insure ignition of the liquid fuel employed at all speeds at which the engine is intended to operate. The opposing end walls of the two pistons and the cylinder walls forming the combustion chamber are without any essential projections or recesses, which would tend to increase the surface of the combustion chamber and thereby increase the heat losses at the periods of high temperature, that is during the last part of the compression stroke and the first part of the working stroke. The piston rod 22 of the piston 23 of the scavenging and air supply pump 4 is secured to the end of the piston rod 16, and the plunger 24 of the

atomizer or vaporizing pump is carried by 65 the piston 23 (see Fig. 1). The end of the working cylinder 2 adjacent to the frame 1 is provided with an annular set of exhaust openings 25 which communicate with the exhaust port 26 by means of the annular space 70 27 and the elbow 28. The opposite end of the working cylinder 2 is provided with a set of air inlet openings 29, which communicate by means of the annular space 30 with the pump 31 whose rear end communicates with the slide valve box of the air pump 4. This pump 31 is made large enough to serve as a reservoir.

On top of the working cylinder 2 and at the central portion thereof, the fuel valve 80 32 is arranged and connected by the pipe 33 to the rear of the air pump 5. Between said pipe 33 and the cylinder of said air pump 5 the pressure valve 34 operates, while the suction valve 35 of the pump is arranged 85 opposite to and below the pressure valve. To operate the fuel valve 32 the fuel pump 36 and the slide valve 37 of the air pump 5, a worm 38 is mounted upon the crank shaft 9 which by means of the worm wheel 90 39 imparts rotation to the shaft 40, the motion of which is in turn transmitted to the shaft 41 by means of the pinions 42 and 43. The motion of shaft 41 is transmitted to shaft 44 by means of the worm 45 and the 95 worm wheel 46. To one end of the shaft 44 an adjustable clamp pin 47 is secured and connected by means of the connecting rod 48 to the plunger of the fuel pump 36 (see Figs. 1 and 3). Upon the shaft 41 is mounted a cam 49 which periodically imparts motion to the lever 50 whose shorter end is connected by means of the rod 51 to the lever 52, the inner end of which operates the fuel valve 32. The fuel valve closes and 100 opens a communication between the working cylinder and the high pressure air pipe 33 and the fuel pipe 53 leading from the fuel pump 36.

The engine operates as follows: Shortly 110 before the working pistons 10 and 15 have reached their outer dead points the working piston 10 uncovers the exhaust openings 25 through which the products of combustion of the previous working stroke escape. Immediately after this the working piston 15 uncovers the inlet openings 29 through which the scavenging and charging air rushes in from the pipe or receiver 31 to drive out the remainder of the products of 115 combustion from the cylinder 2 and also to refill the latter with fresh air. During the following compression stroke of the two working pistons the charging air is so highly compressed that it reaches a temperature sufficiently high to ignite the fuel employed, which enters the working cylinder 2 between the coaxially arranged working pis-

tons 10 and 15 when they have almost reached their inner dead points. The fuel valve 32 is operated when the projection of cam 49 comes into contact with the lever 50, 5 at which instant the atomizing air, which during the previous working stroke was highly compressed, blows the fuel, which has been delivered by the fuel pump 36, in a finely atomized or vaporized condition into 10 the working cylinder 2 wherein it is ignited by the highly compressed charging air. The admission of fuel into the working cylinder 2 is continued during a part of the working stroke, which can be done in such manner 15 that the resulting rise of temperature is, because of the increase of volume, unaccompanied by a substantial change of pressure, at any rate, not in such a degree as in the explosion engine. After the fuel valve 20 32 has been closed, the expansion of the hot gases takes place and continues until near the close of the working stroke, when the working piston 10 uncovers the outlet openings 25 25 again, whereupon the scavenging of the working cylinder 2 begins anew.

Fig. 5 represents a working diagram of my improved engine in comparison with a diagram of a single-piston slow combustion engine, such as is now in common use, in 30 which diagram *a* represents the expansion curve of my improved engine and *b* the expansion curve of the single-piston engine. The difference between the hatched areas *c* and *d* shows the useful work gained per 35 stroke by the new engine as compared with the old engine under otherwise the same conditions. This difference in thermal efficiency is based upon the proportions of the different cylinder surfaces of these two engines 40 and is most favorably influenced by the fact that the fuel is injected midway between the two working pistons when in or near their innermost positions, and by the fact that the opposing faces of the two pistons and the 45 cylinder walls are without any essential projections or recesses whatever. For the compression curve the double-piston engine is likewise advantageous, since with the same compression a higher temperature is attained, which in turn assures a better 50 ignition and a more complete combustion of the fuel employed. Besides this a higher temperature facilitates the starting of the engine and the combustion of difficultly 55 ignitable fuel is made possible. As a result of these conditions, it becomes possible not only to develop the power with greater thermic efficiency, but also to produce an engine which, burning the heavy oils, will 60 be capable of a regulation of speed and output within wide limits, so much so that it has in practice been found possible to vary the speed of an engine of this type from 250 revolutions per minute to 30 revolutions

per minute without encountering any difficulty with the ignition; a result which, so far as I am aware, has not been heretofore attained.

What I claim is:

1. In a slow combustion two-cycle engine, 70 a cylinder having air inlet passages at one end and exhaust passages for the products of combustion at the other end, and two opposingly working pistons in the cylinder which at their point of nearest approach define with the central portion of the cylinder a combustion chamber of small wall area, said parts being so proportioned as to compress the air well above the ignition temperature of the fuel employed, whereby 80 there is attained good scavenging with low temperature of the air charge before compression, rapid compression at relatively low piston speeds and minimum heat losses during the periods of high temperature, in combination with means for injecting fuel into the combustion chamber after the temperature of the air has been brought by compression well above the ignition temperature 85 of the fuel; substantially as described. 90

2. In a slow combustion two-cycle engine, a cylinder of small diameter relative to its effective volume and of smooth bore substantially without recesses or projections having air inlet passages at one end and exhaust passages for the products of combustion at the other end, and two opposingly working pistons in the cylinder which at their point of nearest approach define with the central portion of the cylinder a combustion chamber of small wall area, said parts being so proportioned as to compress the air well above the ignition temperature of the fuel employed, whereby 95 there is attained good scavenging with low temperature of the air charge before compression, rapid compression at relatively low piston speeds and minimum heat losses during the periods of high temperature, in combination with means for injecting fuel into the combustion chamber after the temperature of the air has been brought by compression well above the ignition temperature of the fuel; 100 substantially as described. 105

3. In a slow combustion two-cycle engine, 115 a cylinder of small diameter relative to its effective volume and with a smooth bore substantially without projections or recesses having air inlet passages at one end and exhaust passages for the products of combustion at the other end, and two opposingly working pistons in the cylinder which at their point of nearest approach define with the central portion of the cylinder a combustion chamber of small wall area, said 120 parts being so proportioned as to compress the air well above the ignition temperature of the fuel employed, and the exhaust pas- 125

sages being opened before the inlet passages are opened, whereby there is attained good scavenging with low temperature of the air charge before compression, rapid compression at relatively low piston speeds and minimum heat losses during the periods of high temperature, in combination with means for injecting fuel into the combustion chamber after the temperature of the air

5 has been brought by compression well above

10

the ignition temperature of the fuel; substantially as described.

In testimony whereof I, have signed my name to this specification in the presence of two subscribing witnesses.
